MECHANISM FOR FEEDING COMBUSTION LIQUIDS TO ROCKET APPARATUS

Robert H. Goddard, Roswell, N. Mex., assignor of one-half to The Daniel and Florence Guggenheim Foundation, New York, N. Y., a corporation of New York

Application April 1, 1940, Serial No. 327,257

28 Claims. (Cl. 60—35.6)

This invention relates to rocket apparatus of the type in which flight is sustained by continuous combustion of suitable liquids, such as gasoline and liquid oxygen.

In this application, wherever reference is made to oxygen, it is to be understood that the oxygen is in a liquid state unless otherwise specified, and the term gasoline is to be understood as including other liquid fuels having similar characteristics.

It is the general object of my present invention to provide improved means for continuously feeding gasoline or other liquid fuel and oxygen under high pressures to a combustion chamber.

A further object is to provide improved means for developing power to produce such high pressures and to return condensed products for further use. I also provide improved and novel means for maintaining substantially uniform pressure in the oxygen and liquid fuel containers as the liquids therein are gradually withdrawn.

Further features of my invention relate to automatic control of pressures in my improved feeding mechanism, to provision for automatic closing of certain valves on exhaustion of the liquids in said containers, and to certain safety devices to be described.

My invention further relates to arrangements and combinations of parts which will be herein-after described and more particularly pointed out in the appended claims.

A preferred form of the invention is shown in the drawings, in which

Fig. 1 is a diagrammatic view, partly in section, of my improved feeding mechanism;

Fig. 2 is a transverse sectional view of the oxygen container, taken along the line 2—2 in Fig. 1;

Fig. 3 is a detail view of a modification to be described;

Fig. 4 is a side elevation of a filter cone;

Fig. 5 is a sectional plan view of a nitrogen container;

Fig. 6 is a perspective view of a separator for liquid and gaseous nitrogen;

Fig. 7 is a detail perspective view of a pump and turbine for feeding liquid oxygen;

Fig. 8 is a perspective view of a portion of an insulating covering for the oxygen tank;

Fig. 9 is a side elevation of a detachable coupling;

Fig. 10 is a side elevation of a certain tank-supporting structure;

Fig. 11 is a perspective view of a brace member;

Fig. 12 is a side elevation, partly in section, of

a float device which controls the closing of certain valves on exhaustion of either gasoline or oxygen;

Fig. 13 is a side elevation, partly in section, of a control valve for gasoline or oxygen;

Fig. 14 is a sectional side elevation of a control valve for nitrogen, and actuating mechanism therefor;

Fig. 15 is a sectional side elevation of certain oxygen and gasoline reducing valves and control mechanism therefor;

Fig. 16 is a sectional view of a valve to be described;

Fig. 17 is a detail view, partly in section, of a combined check valve and coupling member;

Fig. 18 is a front elevation, partly in section, of a solenoid-operated three-way valve;

Fig. 19 is a sectional elevation of a special check valve to be described;

Fig. 20 is an enlarged sectional elevation of a shielded vent and check valve to be described;

Fig. 21 is a diagrammatic side elevation of a launching frame;

Fig. 22 is a detail front elevation of a rotary pump, partly in section to show a sealing device; and

Fig. 23 is a partial sectional front elevation showing an auxiliary turbine nozzle.

In Fig. 1, I have shown a diagrammatic assembly of the various parts of my improved feeding mechanism in association with a combustion chamber 16 and nozzle 17, which latter parts are shown on a reduced scale as in themselves they form no part of the present invention. It will

be understood that all of the parts shown in Fig. 1 will be assembled within a suitable rocket casting, with the combustion chamber 16 and nozzle 17 disposed at the rear end thereof, as shown, for instance, in my prior Patent No. 2,183,311.

Briefly described, my invention includes an oxygen tank 20, a gasoline tank 40, and a nitrogen tank 70, all at moderate pressures. Liquid oxygen is delivered from the tank 20 through a pipe 21 (Fig. 1) and valve 22 to a pump 23

which is connected to the combustion chamber 16 through a pipe 24 and valve 25. The pump 23 is driven by a turbine 26 and greatly increases the pressure of the oxygen before delivery thereof to the combustion chamber.

Gasoline is similarly delivered through a pipe 41 and valve 42 to a pump 43 which is connected through a pipe 44 and valve 45 to the combustion chamber 16. The pump 43 is driven by a turbine 46 and feeds gasoline at high pressure to the combustion chamber.

The turbines 28 and 46 may be conveniently operated by steam from a boiler 50 which is delivered to the turbines through a pipe 51 and branch pipes 52 and 53. The boiler 50 must be of very light weight but the details of construction of the boiler form no part of my present invention. It may be briefly stated that water is evaporated and steam formed in the boiler 50 by direct contact of the water with hot gases resulting from the combustion of a mixture of oxygen delivered through a branch pipe 27 and gasoline delivered through a branch pipe 47. The pipe 27 is provided with a reducing valve 29 and the pipe 47 with a reducing valve 48.

Exhaust steam from the turbines 28 and 46 is delivered through pipes 50^a, 51^a and 52^a to a condenser 53^a in which the steam is condensed by the evaporation of a spray of liquid oxygen supplied through a branch pipe 55 and a valve 56. The condensed steam is then returned through a pipe 57, pump 58 and pipe 59 to the boiler 50. The pump 58 is driven by a small turbine 60 which receives operating steam through a branch pipe 61 and a valve 61^a. The details of construction of the condenser 53^a form no part of my present invention.

The oxygen gas evaporated in the condenser 53^a is returned to the oxygen tank 20 through a pipe 62. This gas also contains more or less water vapor and also carbon dioxide from the boiler 50, both of which substances freeze at temperatures above the freezing point of oxygen.

In order to keep these solidified particles of water or carbon dioxide from clogging the oxygen delivery pipe 21, I introduce the pipe 62 tangentially into the tank 20, as shown in Fig. 2, so that the water and carbon-dioxide will solidify near the outer wall of the tank. I also provide a perforated conical filter plate 64 (Figs. 1 and 4) in the tank 20 by which these solid particles will be separated and prevented from falling to the bottom of the tank. The plate 64 may be covered with a fine wire mesh screen if considered desirable.

It will be noted that the pumps 23 and 43 and the turbines 28 and 46 are oppositely disposed to equalize weight, and it is also desirable to have these units rotate in opposite directions to neutralize gyroscopic force.

It is important that gas pressure be maintained substantially constant in the tanks 20 and 40 during the flight of the rocket apparatus, as these tanks are necessarily made with very thin walls in order to save weight and are stiffened by internal pressure. The tanks may also be externally reinforced as shown in my prior Patent No. 2,109,529. A constant internal pressure is also desirable to assist the pumps 23 and 43 in delivering liquids therefrom at uniform high pressure.

In order to maintain such uniform pressure in the tanks 20 and 40 as the liquids are gradually withdrawn, I provide the auxiliary tank 70, preferably submerged in oxygen within the tank 20 as shown in Fig. 1. The tank 70 may be filled with a liquified inert gas such as liquid nitrogen by injecting nitrogen gas under pressure through a feed pipe 71, valve 72 and coil 73, said coil being connected at its inner end to the nitrogen tank 70. If the nitrogen gas is injected after the tank 70 is submerged in liquid oxygen, and if a substantial pressure, such as 75 lbs. is maintained, the nitrogen gas will be condensed in the coil 73 and the tank 70 will be gradually filled with liquid nitrogen. When the tank 70 is filled, the valve 72 may be manually closed.

It is desirable to prevent the liquid nitrogen from falling below the temperature of the liquid oxygen, due to nitrogen evaporation in the tank 70 as the nitrogen supply is drawn off during the operation of the rocket apparatus. I accordingly provide a series of transverse tubes 74 (Figs. 1 and 5) through which oxygen may circulate to equalize the temperature of the nitrogen.

In order to change the liquid nitrogen to a nitrogen gas under a moderate pressure, the liquid nitrogen is delivered through a jacketed tube 75, a jacketed reducing valve 76, and a pipe 77 to a coil 78 which surrounds the combustion chamber 16 and nozzle 17, as shown in Fig. 1. Heat is transferred from the combustion chamber and nozzle to the nitrogen in the coil 78, raising the temperature thereof and evaporating the liquid nitrogen so that nitrogen gas is delivered to the return pipe 79.

Small drops or particles of liquid nitrogen may be mingled with the nitrogen gas, and it is not desirable that this liquid nitrogen enter the oxygen tank 20 where it would dilute the liquid oxygen. Accordingly, the return pipe 79 is connected to a separator 80 (Fig. 6) where the liquid nitrogen, together with a part of the nitrogen gas, is delivered through centrifugal action to a pipe 81 and dry nitrogen gas is delivered to a pipe 82. The pipe 81 connects through a check valve 83 to the upper end of the gasoline tank 40, and the pipe 82 connects through a check valve 84 to the upper end of the oxygen tank 20. Nitrogen gas under pressure thus fills the upper ends of the tanks 20 and 40 and maintain substantially constant pressure therein, regardless of the withdrawal of liquids therefrom.

The gasoline in the tank 40 is at a relatively high or ordinary temperature, so that any drops of liquid nitrogen delivered through the pipe 81 will be immediately evaporated in the tank 40 and will not dilute the gasoline. The check valves 83 and 84 in the pipes 81 and 82 open toward the tanks 20 and 40 but prevent flow in a reverse direction, so that there can be no transfer of gasoline vapor to the tank 20 or oxygen vapor to the tank 40. Explosive mixtures are thus avoided.

The jacketed reducing valve 76 is controlled in its operation by the pressure in a pipe 85, the upper end of which is connected into the pipe 82 previously described. The construction and operation of the valve 76 is shown in detail in Fig. 14.

The reducing valve 76 (Fig. 14) comprises a valve member 86 mounted at the upper end of a rod 81 guided in a bearing 82 and extending downward through a bellows packing 83 to the bottom plate of a bellows member 84 and to a lever 85. A spring 86 in the bellows member 84 normally holds the valve open. The control pipe 85 previously described is connected into the space between the bellows member 84 and the casing 87. Obviously a sufficient increase in pressure in this restricted space will compress the spring 86 and raise the valve member 86 to closed position, the bellows member 84 acting merely as packing.

The lever 85 may be provided with a pull cord 88 by which the valve 76 may be held closed except during rocket propulsion. A jacket tube 89 surrounds the reducing valve 76 and is freely connected to the interior of the tank 20, so that the tube 89 is at all times filled with liquid oxygen which prevents gas-bind in the reducing valve.

An alternative method of supplying pressure to

a liquid fuel tank 40^a containing a fuel of high vapor pressure, such as butane, is shown in Fig. 3, where a small part of the liquid fuel is delivered through a pipe 100 and reducing valve 101 to a coil 102 surrounding a combustion chamber 16^a and nozzle 17^a thereby evaporating the liquid fuel and supplying vapor under reduced pressure through a return pipe 103 to the upper end of the tank 40^a. A cross connection 104 from the return pipe 103 to the reducing valve 101 regulates the operation of this modified apparatus, the construction and operation of the valve 101 being similar to that of the reducing valve 76 shown in Fig. 14 and previously described. Both the coils 18 and 102 may be wound on the same chamber and nozzle.

The pressure which causes the butane or other low boiling fuel to flow from the tank 40^a through the coil 102 will be the difference in head between the tank 40^a and the chamber 16^a, and also the pressure due to the acceleration of the rocket apparatus during flight. As both the liquid and the evaporated gas are confined in a single closed system, the gas pressure will be substantially the same both above and below the body of liquid and the natural down-flow of the liquid by gravity will not be affected by the gas pressure. The rate of flow will, however, be influenced by changes in acceleration of the aircraft and would result in an excessive rise in gas pressure, if not controlled by the reducing valve 101 which is responsive to gas pressure in the return pipe 103. A construction similar to that shown in Fig. 3 may also be provided for the oxygen tank 20 if so desired, in which case the nitrogen tank may be omitted.

The construction and operation of the pressure-reducing valves 29 and 49 in the boiler connections is shown in detail in Fig. 15. The valve 29 comprises a valve member 110 which, when free to move, is closed by a spring 111 and thus interrupts flow through the pipe 27. A rod 112 is secured in a plate 113 and is slidable in a fixed guide 115. A spring 116 tends to force the rod 110 downward to depress and unseat the valve member 110. The oxygen pressure in the space between a bellows member 117 and the casing 118 resists the pressure of the spring 116.

Consequently, an increase in pressure in the pipe 27 lifts the rod 112 and allows the valve member 110 to move toward closed position, while a decrease in pressure allows the spring 116 to depress the rod 112 and valve member 110, thereby allowing increased flow through the pipe 27. A jacket 119 surrounds the reducing valve 29 and is connected by a pipe 119^a to the pipe 55, which in turn connects through the delivery pipe 21 to the oxygen tank 20. Gas-bind of the oxygen valve 29 is thus prevented.

The gasoline reducing valve 49 is of exactly similar construction, except for omission of the jacket 119 and oxygen connection 119^a. The reducing valve 49 comprises the valve member 120, the spring 121, the rod 122, the spring 126, bellows member 127 and casing 128, all as previously described.

It is sometimes desirable to allow the reducing valves 29 and 49 to close, regardless of the pressures in the pipes 27 and 47. Accordingly I connect the upper ends of the rods 112 and 122 to levers 130 and 131, which levers have a pin and slot connection to a stud 132 carried by a yoke or frame 133 which is connected to the upper end of a rod 134. The lower end of the rod 134 is fixed to a plate 135 forming the lower end of a bellows

member 136 enclosed in a casing 137. A pipe 138 is connected to the space between the bellows member 136 and the casing 137. If gas under pressure is admitted through the pipe 138, the bellows member 136 will be compressed, raising the yoke 133 and levers 130 and 131 and thus lifting the rods 112 and 122 away from the valve members 110 and 120, which are then free to be closed by their springs 111 and 121.

10 The gas under pressure for the pipe 138 may be initially supplied through a hose connection 140 (Figs. 1 and 9), a check valve 141 and a coupling member 141^a. A latch 142 normally secures the hose and coupling together but may be released by a manual pull on a cord 143. The valve and coupling 141 (Fig. 1) is connected by a pipe 144 to a three-way valve 145 (Fig. 18) which may be set to connect the pipe 144 to the pressure pipe 138 previously described or to vent the pipe 138.

20 The detail structure of the check valve 141 and coupling member 141^a is shown in Fig. 17 and comprises a check valve element 146 seated against a conical seat 147 by a spring 148, the valve stem being slidable in a perforated guide-plate 149.

25 The three-way valve 145 is shown in detail in Fig. 18 and comprises a rotary valve member 155 mounted in a casing having ports 156, 157 and 158 to which the pipes 144 and 138 and a vent pipe 159 are connected. The rotary valve member 155 is provided with an arm 155^a connected to a plunger 240^a of a solenoid 140, the operation of which will be hereinafter described.

30 After sufficient vapor pressure is developed in the oxygen tank 20, or after sufficient outside pressure has been supplied to the tank 20 through the hose 200, the hose 140 may be disconnected. The pressure in the pipe 138 will then be supplied through a pipe connection 150 from the upper end of the tank 20. A check valve 151 prevents reverse flow in the pipe 150. Branch pipes 152 and 153 supply pressure to liquid seal devices in the pumps 23 and 43, the specific construction of which forms no part of my present invention.

35 One form of such a liquid seal device is shown in Fig. 22 and comprises an annular flange 250 on the pump shaft 251 which is engaged by an annular disc 252 which loosely encircles the pump shaft 251 and which forms the movable outer end of an annular bellows member 253, to which the pipe 152 is connected through a channel 254 in the pump casing. When pressure is applied through the pipe 152, the disc 252 is forced firmly in contact with the flange 250, thus effectively sealing the pump bearing and preventing leakage of liquid from the pump 23. A precisely similar sealing device may be provided for the pump 43.

40 The preferred construction of the oxygen valve 25 in the pipe 24 is shown in detail in Fig. 13 and comprises a valve 160 supported on a rod 161 and extending downward through a bellows packing 162 to a lever 163 having a pull cord 164.

45 When the apparatus is not in operation, the valve 25 may be closed manually by use of the cord 164, but otherwise the valve 25 is normally open. The gasoline valve 45 in the pipe 44 is of similar construction and operation.

50 A spark-plug or other suitable igniter 166 is provided for starting combustion in the chamber 16 when the apparatus is to be put in operation. Because of the small clearance in the pumps 23 and 43, a vent pipe 167 (Fig. 1) connects the upper end of the oxygen feed pipe 24 through a special check valve 168 to the upper end of the oxygen tank 20. A similar vent pipe 170 connects

the gasoline feed pipe 44 through a special check valve 171 to the upper end of the gasoline tank 40. A shut-off valve 171^a may also be provided in the pipe 170 adjacent the tank 40. The special check valves 168 and 171 open away from the tanks 20 and 40 and are normally slightly open to vent the pumps 23 and 43 but close automatically as soon as the pumps begin to develop any substantial pressure.

The construction of the special check valve 168 is shown in detail in Fig. 19 and comprises a valve element 172 normally held slightly away from its conical seat 173 by a light spring 174, the valve stem being slideable in a perforated guide member 174^a. When the oxygen pump 23 starts to operate, a rapid flow takes place in the direction of the arrows *k* in Fig. 19, which closes the check valve 168 and holds it closed so long as the pump is in active operation. The construction of the special valve 171 is identical with that of the valve 168 above described.

A safety valve 175 is provided for the tank 20, to relieve any excessive pressure caused by evaporation of the liquid oxygen. This safety valve is preferably surrounded by a light metal shield 176 to prevent freezing of the valve. The shield is mounted in spaced relation to the valve and has a vent opening of reduced cross section at the top thereof. As the oxygen gas escapes, frost may form on the outside of the shield 176 but the oxygen gas, being perfectly dry, will not form any frost on the valve 175 or within the shield 176. Any water which may have been present in the liquid oxygen will have been previously frozen to solid particles and deposited on the screen 64.

A vent and check valve 177 in the top of the oxygen tank 20 is provided for venting the tank while it is being filled preparatory to starting. This vent valve is allowed to close under tank pressure after the tank has been filled. This valve 177 is provided with shields 178 to prevent freezing, as previously described for the valve 175. The detailed construction of the valve 177 may be as shown in Fig. 20 and comprises a valve element 177^a normally pushed upward and seated by a spring 177^b but held open by a crosspin 177^c while the oxygen tank 20 is being filled. After the tank is full, the pin 177^c is withdrawn and the valve element 177^a moves upward against its seat under the influence of the spring 177^b and also of the pressure in the tank 20. The shields 178 are also clearly shown in Fig. 20.

A safety valve 179 is provided for the gasoline tank 40 and a similar safety valve 180 for the nitrogen tank 70, the valve 180 being located in the feed line to the nitrogen tank.

A special vent valve 181 (Figs. 1 and 16) is provided in the gasoline feed pipe 44, which valve comprises a hinged valve member 182 adapted to seat in either one of two openings 183 or 184. When in the full line position shown in Fig. 16, the member 182 closes the lower end of the pipe 144 and leaves the vent 184 above the valve open. When the member 182 is moved by operation of a pull rod 182^a, manually or otherwise, to the dotted line position, the vent opening is closed and the pipe 44 is open. When the apparatus is not in use, the valve 182 is moved to the full line position, shutting off the lower end of the pipe 44 and preventing gasoline vapor from drifting into the combustion chamber 16 and possibly forming an explosive mixture.

For additional safety, I provide a branch connection 186 from the nitrogen gas pipe 78 to the combustion chamber 16. This pipe is controlled

by a shut-off valve 187 and may be used to inject a small amount of nitrogen gas into the combustion chamber to dilute any oxygen present and thus prevent a serious explosion on ignition, even if some residual gasoline vapor has been left in the chamber.

Auxiliary starting nozzles of well known construction are provided in the turbines 28 and 48 and provision is made for supplying pressure from an outside source for initially starting the turbines, such provision comprising a detachable hose 190 latched to a check valve 191 and coupling member 190^a which is connected through a pipe 192 and branch pipes 193 and 194 to the turbines 28 and 48 respectively. The specific construction of the auxiliary nozzles forms no part of my present invention but may be as disclosed in Fig. 23.

The tanks 20 and 40 are preferably provided with semispherical ends, as shown in Figs. 1 and 10, and may be separated and held in fixed relation by a skeleton frame structure comprising rings 197 and braces 198 (Fig. 10), which parts are preferably tubular and very light and maintained under pressure. They may also be reinforced with a wire winding, all as set forth in my prior Patents Nos. 2,090,038 and 2,109,529.

An additional pressure hose 200 is detachably connected through a check valve 201 and coupling member 201^a to the nitrogen gas pipe 78, so that gas pressure may be supplied to the tanks 20 and 40 before the nitrogen pressure apparatus is started in operation.

Any suitable frame-work may be provided for launching my improved rocket craft R and such frame-work is shown diagrammatically in Fig. 21, which shows the craft R held in upright position by braced guide-members 202, which provide a vertical guideway open at its upper end.

As the disconnecting and pulling off of the hoses 140, 190 and 200 may exert a considerable sidewise pull against the casing of the rocket apparatus, I preferably provide a brace member 204 (Figs. 11 and 21) hinged to a fixed outside support 205 and having an end portion 206 curved to fit the surface of the rocket craft R. A stop 207 normally supports the member 204 but said member is free to swing toward the dotted line position in Fig. 11 and away from the rocket as the upward flight thereof begins.

It is desirable to have the oxygen tank 20 effectively heat-insulated prior to flight to prevent oxygen evaporation, and it is also desirable to remove a substantial part of this insulating covering when flight is about to take place. If any boiling of the oxygen occurs during flight, this is not objectionable but on the other hand assists in maintaining pressure in the oxygen tank and helps to conserve the supply of liquid nitrogen.

I accordingly provide a felt covering for the lower portion and sides of the tank 20 which comprises an end pad 210 (Fig. 1) which remains permanently in position and two semi-cylindrical pads 211 (Fig. 8) which are hinged together at one side of the tank as indicated at 212, and are latched at the opposite side as indicated at 213. A pull cord 214 provides means for quickly unlatching the pads 211 which then swing apart and may be removed by a further pull on the cord 214 or in any other convenient manner. The pads 211 are provided with suitable light metal frames 215 to retain them in shape.

Whenever either the oxygen or the gasoline

supply is exhausted, it is desirable to close both valves 25 and 45 promptly, so that the remaining liquid in the tank not exhausted may not continue to feed into the combustion chamber after combustion can no longer be sustained and thus be wasted. The valves 25 and 45 are accordingly provided with suitable additional electrical control mechanism, such as solenoid plungers 220 and 220^a (Fig. 13) and solenoid coils 221 and 221^a connected by wires 222 to a suitable supply of electricity. This circuit is controlled by two switches 224, one of which is shown in Fig. 12. These switches are mounted in parallel, with one switch associated with the oxygen tank 20 and the other with the gasoline tank 40.

Each switch 224 comprises normally separated contacts 225 (Fig. 12) and a packed plunger 226 connected to a lever 227 within the tank 20 or 40 and provided with a float 228. When the liquid in either tank is exhausted, the associated float 228 falls, pressing its plunger 226 against the coacting contacts 225 and thus completing the solenoid circuit. The solenoids 220 and 220^a in turn force the valve members 160 (Fig. 13) upward and shut off the oxygen feed pipe 24 and the gasoline feed pipe 44. A slotted and perforated shield member 229 covers the float 228, so that abrupt movement of the liquid in the tank cannot accidentally depress the float and close the contacts.

Operation

The use and operation of many parts of my improved feeding mechanism have been clearly indicated in the preceding description but a brief general statement of the operation of the entire feeding mechanism appears desirable.

Starting with the tanks empty, the hoses 140, 190 and 200 will be coupled to the check valves 141, 191 and 201, and a similar hose connection will be made to the nitrogen feed pipe 71. A suitable gas, under pressure, is admitted through the pipes 140 and 144 to the three-way valve 145, which valve is set to connect the pipe 144 to the pressure pipe 138 and to the branch pipes 152 and 153. Pressure in the branch pipes will seal the bearings of the pumps 23 and 43 and prevent leakage therethrough while the pumps are at rest, the sealing means being disclosed in Fig. 22 and being more fully shown and described in my prior Patent #2,281,971, issued May 5, 1942. After the oxygen tank 20 has been filled and is under pressure, this pressure will then be communicated through the pipe 150, which connects into the pipe 138 through the check valve 151. This valve prevents reverse flow of gas when the tank 20 is at a lower pressure.

Pressure in the pipe 138 also causes the bellows member 136 (Fig. 15) to operate to release the reducing valve members 110 and 120 and allow these valves to close, even when there is no pressure in the boiler 50. This avoids leakage of oxygen and gasoline through the boiler to the turbines 26 and 46, which would not only be wasteful but might cause an explosive mixture.

The tanks 20 and 40 are supplied with liquid oxygen and gasoline respectively through feed pipes 230 and 231 having shut-off valves 232 and 233 and adapted to receive suitable hose connections. After the tank 20 is filled, the vent check valve 177 is released and allowed to close.

The nitrogen tank 70 is filled by feeding nitrogen gas under pressure through a hose connection to the pipe 71, coil 73 and tank 70, all as previously described. The reducing valve 76 is

at this time closed. After the tanks 20, 40 and 70 are filled, the hose connections to the pipes 230, 231 and 70 are disengaged.

The three-way valve 145 is then set to vent the pipe 138, releasing the pressure on the pump bearings, and also freeing the valves 29 and 49 which control the flow of oxygen and gasoline to the boiler 50 and which thus control the production of steam to drive the turbines 26 and 46. Combustion may be started in the boiler by an igniter 235, previously rendered active.

A short time before starting flight, the valve 22 is opened to allow liquid oxygen to flow to the pump 23 and valve 25. It is desirable to keep the valve 22 closed until shortly before flight, as liquid oxygen remaining for any considerable time in the pump 23 or in the pipe connections below the valve 22 would cause these parts to accumulate frost and eventually freeze solid, thus becoming inoperative. The valves 25 and 45 are now opened to allow oxygen and gasoline to flow into the combustion chamber 16, the igniter 166 having been previously rendered operative and the vent valve 181 having been previously closed to the outside air. As soon as the pumps start, pressures are built up in the pipes 167 and 170, which pressures close the check valves 168 and 171.

Nitrogen gas from an outside source and under substantial pressure, as 50 to 100 lbs. per square inch, is initially supplied through the hose 200 and check valve 201 to the pipes 79, 81 and 82 and thence to the tanks 20 and 40. Also, outside gas or steam under heavy pressure is supplied through the hose 190 and pipes 192, 193 and 194 to operate the auxiliary starting nozzles in the turbines 26 and 46. Before flight actually commences, the felt pads 211 are unlatched by a pull on the cord 214 and are removed from the oxygen tank 20.

After combustion is under way in the combustion chamber 16 and in the boiler 50, the spark-plugs or igniters 166 and 235 may be disconnected or rendered inoperative. As soon as the boiler 50 has developed working pressure, the hose connections 140, 190 and 200 are disconnected.

It is desirable that the connections to the pipes 140, 190 and 200 be removed quite promptly for the following reasons:

If pressure is maintained too long through the hose 190, the speeds of the turbines 26 and 46 will become excessive. This outside operating force should be discontinued as soon as the boiler 50 has developed working pressure. If the tanks 20 and 40 are supplied for too long a time with outside nitrogen pressure through the hose 200, the liquid nitrogen in the tank 70 will not flow through the jacket coil 78, and the temperature of the coil 78 and also of the combustion chamber 16 and nozzle 17 will become excessive and much higher than the temperature for which they were designed. The hose 140 can be disconnected, as pressure for the pump bearings will now be supplied from the oxygen tank through the pipe 150.

The apparatus is now in condition for sustained flight, which flight will normally continue until the supply of one or the other of the combustion liquids is exhausted, whereupon one of the float-controlled switches 224 will be closed, thus energizing the solenoids 221 and 221^a (Fig. 13) to shut off from the combustion chamber the exhausted tank and also the other tank which is not yet exhausted.

Closing of either switch 224 also energizes the solenoid 248 to close the three-way valve 148, putting pressure on the pump seals and releasing the valve members 110 and 120 (Fig. 15) to close as previously described. These pump seals must be closed to prevent loss of pressure in the tanks 20 and 40, and the valve members 110 and 120 in the valves 28 and 48 must be allowed to close to prevent similar loss of pressure through the boiler and thence out through the regular turbine nozzles.

These operations are also necessary to prevent the burning out of the combustion chamber, which is commonly cooled by a film of liquid gasoline, as set forth in my prior Patents Nos. 2,016,921 and 2,035,800.

The rigidity of the thin walls of the tanks 20 and 40 also depends quite largely on the maintenance of substantial pressure in these tanks during flight. If excessive gas pressure, however, is developed by evaporation or otherwise in any of the tanks 20, 40 or 70, this pressure will be relieved through the safety valves 175, 178 and 180 respectively. The pressure and rate of feed of gasoline and oxygen to the boiler may be controlled by changing the pressure of the springs 116 and 126 (Fig. 15) and the flow of condensed water to the boiler may be controlled by the valve 61* which supplies steam to the turbine 60. Through these several adjustments the speed of the pumps 23 and 43 may be varied.

On recovery of the apparatus after flight, the pressure in the tanks 20, 40 and 70 may be reduced if desired, by manually opening the safety valves on said tanks.

From the foregoing description it will appear that I have provided new and improved mechanism for continuously feeding combustible liquids to a combustion chamber during the flight of a rocket, together with means for maintaining substantially uniform pressure in the storage tanks as the supply of liquids is gradually diminished. I have also provided auxiliary devices of novel construction and particular design to operate under the unusual conditions arising from the use of an extremely cold oxidizing liquid such as liquid oxygen.

Having thus described my invention and the advantages thereof, I do not wish to be limited to the details herein disclosed, otherwise than as set forth in the claims, but what I claim is:

1. In a rocket, combustion apparatus comprising separate tanks for combustible and oxidizing liquids, means to intermingle said liquids and to produce continuous combustion thereof, and means to evaporate an inert liquid to an inert gas under pressure and to automatically supply said inert gas under uniform pressure to those parts of said tanks not filled by said combustible and oxidizing liquids, and said inert gas thereby maintaining substantially uniform pressure in both of said tanks as the liquids are withdrawn therefrom.

2. In a rocket, combustion apparatus comprising a tank containing combustible liquid, a second tank containing a very cold oxidizing liquid, a third tank immersed in said oxidizing liquid and containing an inert liquid, and means to evaporate a portion of said inert liquid to produce gas pressure in said first and second tanks as said tanks are gradually emptied during flight.

3. The combination in a rocket as set forth in claim 2, in which the combustion apparatus embodies a combustion chamber and nozzle, and in which said inert liquid is progressively evap-

orated in a coil surrounding said chamber and nozzle, the gas from said evaporation being delivered to said first and second tanks to maintain pressure therein.

4. In a rocket, combustion apparatus comprising separate tanks containing combustible and oxidizing liquids, a combustion chamber and nozzle, an auxiliary boiler, pumps to feed said liquids to said combustion chamber under high pressure, driving means for said pumps, and means to produce a gas under pressure in said boiler for the driving means of said pumps by combustion of a portion of said liquids in said boiler at reduced pressure.

5. The combination in a rocket as set forth in claim 4 in which a condenser is provided to receive the exhaust fluid from said driving means and which is effective to condense said exhaust fluid by evaporation of a portion of the oxidizing liquid in said condenser.

6. The combination in a rocket as set forth in claim 4, in which automatic means is provided to regulate the reduced pressures of the combustible and oxidizing liquids delivered to said boiler.

7. The combination in a rocket as set forth in claim 4, in which means is provided which is responsive to changes in liquid level in said tanks and which is effective to automatically shut off all supply of said liquids to said boiler when liquid is exhausted in either of said tanks.

8. The combination in a rocket as set forth in claim 4, in which means is provided which is responsive to changes in liquid level in said tanks and which is effective to automatically shut off the supply of either liquid to said combustion chamber when the other liquid is exhausted.

9. In a rocket apparatus, a combustion chamber, a pipe to feed liquid fuel thereto, a shut-off valve in said pipe, and additional means to close the lower part of said feed pipe at a point adjacent to said combustion chamber, the upper part of said feed pipe having a vent opening closely adjacent to said additional closing means, and said additional closing means being alternately effective to close said vent opening when said feed pipe is open to said combustion chamber and to open said vent opening to provide an escape for combustible vapors when said feed pipe is closed by said additional closing means.

10. In a rocket apparatus, a tank for liquid oxygen, means to inject mixed steam and vapors into said tank in a tangential direction, whereby congealed particles will be thrown to the outside of said tank, and means to collect said particles.

11. In a rocket apparatus, a tank for liquid oxygen, means to inject mixed steam and vapors into said tank in a tangential direction, whereby congealed particles will be thrown to the outside of said tank, and a conical screen to collect said particles near the outer wall of said tank.

12. In a rocket apparatus, a tank for liquid oxygen, an inner tank for an inert liquified gas immersed in said liquid oxygen, said inert liquid on evaporation providing an inert gas under pressure, a connection between said inner tank and said oxygen tank through which said inert gas under pressure provides a part of the operating pressure in said oxygen tank, and means to keep the temperature of said two liquids substantially equal as the inner tank is gradually emptied and as a part of said inert liquid evaporates, said means comprising heat exchange devices associated with said inner tank and constructed and arranged to bring portions of liquid oxygen into intimate heat exchange relation with the remain-

75

ing portion of inert liquid, thereby maintaining the temperature of said inert liquid substantially at the temperature of the liquid oxygen and thereby preventing a drop in pressure in said inner tank as said inert liquid evaporates.

13. In a rocket apparatus, tanks for liquid fuel, liquid oxygen and a liquid inert gas, means to evaporate said liquid inert gas and deliver said gas under pressure to said fuel and oxygen tanks, and means to separate particles of said liquid inert gas from the gas delivered to said oxygen tank and to deliver said particles to said fuel tank.

14. The combination in a rocket apparatus as set forth in claim 13, in which means is provided in said inert gas connections to prevent flow of liquid fuel to said oxygen tank or oxygen to said fuel tank.

15. In a rocket apparatus, separate tanks for liquid fuel and oxygen, separate valves controlling the flow from said tanks, and means to effect operation of said valves to prevent flow of liquid from either tank after the other tank has been emptied, said means comprising a separate float associated with each tank, an electric circuit controlled thereby, and a pervious shield which prevents movement of said float by movement of liquid in said tank.

16. In a rocket apparatus, a pump, fluid-operated means to drive said pump, pressure-operated sealing means for the bearings of said pump, a boiler to supply steam to drive said pump, a tank for liquid fuel, a tank for liquid oxygen, means to feed said liquid fuel and said liquid oxygen from said tanks to said boiler, a single valve controlling the operation of said feeding means and the operation of said sealing means, and devices effective to render said single control valve operative to cause stopping of the feed of any liquid to the boiler and also to cause pressure to be applied in said sealing means, all in the event of exhaustion of the supply of liquid in either of said tanks.

17. In a rocket apparatus, a liquid fuel tank, a combustion chamber, a coil about said chamber, the lower end of said tank being connected to the upper and cooler end of said coil and the lower and heated end of said coil being return-connected to the top of said tank, whereby liquid fuel vapor pressure is maintained in said tank as liquid fuel is withdrawn therefrom.

18. The combination in rocket apparatus as set forth in claim 17, in which a reducing valve in the tank-to-coil connection is controlled by the liquid fuel vapor pressure in the return connection.

19. In a rocket apparatus, a combustion chamber, pipes supplying liquid fuel and a liquid oxidizing agent to said chamber, means to ignite said fuel, and means to admit a portion of inert gas to said chamber prior to initial ignition to moderate the initial combustion.

20. In a rocket apparatus, a combustion chamber, a liquid fuel tank, a pipe to feed liquid fuel from said tank to said chamber, means to shut off the lower part of said feed pipe, means to vent an adjacent upper part of said feed pipe through a connection which extends to the top of the liquid fuel tank, said venting means including a check valve effective to open toward said feed pipe on substantial drop in pressure in said vented upper part of said feed pipe, and means to introduce liquid fuel under pressure to said vented upper part and thereby closing said check valve

in said venting means prior to the placing of said rocket apparatus in operation.

21. In a rocket apparatus, a combustion chamber, a pipe to feed liquid fuel thereto, a liquid fuel tank, means to close one part of said feed pipe, a vent pipe connecting an adjacent part of said pipe to the top of the liquid fuel tank, a check valve in said vent pipe closable toward said tank by excess of pressure in said adjacent part, and means to admit liquid fuel under pressure to the vented part, thereby closing said check valve prior to the operation of the said rocket apparatus.

22. In a rocket apparatus, a combustion chamber, a liquid oxygen tank, a pipe to feed liquid oxygen from said tank to said chamber, means to shut off the lower part of said feed pipe, means to vent an adjacent upper part of said feed pipe through a connection which extends to the top of the liquid oxygen tank, said venting means including a check valve effective to open toward said feed pipe on substantial drop in pressure in said vented upper part of said feed pipe, and means to introduce liquid oxygen under pressure to said vented upper part and thereby closing said check valve in said venting means prior to the placing of said rocket apparatus in operation.

23. In a rocket apparatus, a combustion chamber, a pipe to feed liquid oxygen thereto, a liquid oxygen tank, means to close one part of said feed pipe, a vent pipe connecting an adjacent part of said pipe to the top of the liquid oxygen tank, a check valve in said vent pipe closable toward said tank by excess pressure in said adjacent part, and means to admit liquid oxygen under pressure to the vented part, thereby closing said check valve prior to the operation of said rocket apparatus.

24. In a rocket apparatus, a combustion chamber, a pipe to feed liquid oxygen thereto, a liquid oxygen tank, means to shut off the lower part of said feed pipe, a vent pipe connecting an adjacent part of said pipe to the top of the liquid oxygen tank, a check valve in said vent pipe closable toward said tank by excess pressure in said adjacent part, and means for pre-cooling the vented parts by the admission of liquid oxygen thereto prior to the operation of said rocket apparatus.

25. In a rocket apparatus, a pump, fluid-operated means to drive said pump, pressure-operated sealing means for the bearings of said pump, a boiler to supply steam to drive said pump, a tank for liquid fuel, a tank for liquid oxygen, means to feed said liquid fuel and said liquid oxygen from said tanks to said boiler, pressure-regulating valves for said fuel and oxygen feeding means effective to maintain a predetermined pressure in said boiler, and a single valve effective to control the operation of said sealing means and also to control the operation of said pressure-regulating valves for said feeding means.

26. In a rocket, combustion apparatus comprising separate tanks containing combustible and oxidizing liquids, a combustion chamber and nozzle, pumps to feed said liquids to said combustion chamber under high pressure, sealing means for said pump, turbines to drive said pumps, a boiler to supply steam to drive said turbines, valves to regulate the pressure of the liquids fed to said boiler, a control valve for said regulating valves, and auxiliary means to supply gaseous pressure to operate said turbines, said sealing means and said control valve when preparing said rocket for flight.

27. The combination in a rocket as set forth in claim 26, in which said auxiliary means comprises a plurality of external hoses detachably connected to the parts in said rocket actuated thereby.

28. The combination in a rocket as set forth in claim 26, in which said auxiliary means comprises

a plurality of external hoses detachably connected to the parts in said rocket actuated thereby, and in which an external brace is provided to take the lateral strain when said hoses are disconnected, said brace being thereafter displaceable in the direction of flight.

ROBERT H. GODDARD.
